UNITED STATES PATENT OFFICE.

WILLIAM H. SHAINLINE, OF NORRISTOWN, PENNSYLVANIA.

DYEING-MACHINE.

1,129,128.

Specification of Letters Patent. Patented Feb. 23, 1915.

Application filed April 10, 1914. Serial No. 830,861.

To all whom it may concern:

Be it known that I, WILLIAM H. SHAINLINE, of Norristown, in the county of Montgomery and State of Pennsylvania, have invented certain new and useful Improvements in Dyeing-Machines, whereof the following is a specification, reference being had to the accompanying drawings.

The invention relates more particularly to dyeing machines wherein the dye liquor is caused to circulate through the material under treatment.

An object of the invention is to provide a dyeing machine with a supporting cage for the material under treatment, which supporting cage is capable of being rotated while immersed in the dye liquor, and is provided with a central chamber in which are oppositely disposed devices for causing a circulation of the dye liquor from the said central chamber of the cage, outwardly in all directions toward the outer wall of the cage, or inwardly in all directions through the outer wall of the cage toward the center thereof.

A further object of the invention is to provide means whereby the supporting cage may be rotated in the tank containing the dye liquor, by devices which extend through a peripheral opening in the tank.

A further object of the invention is to provide a device of the above character, with means whereby the tank for the dye liquor is so supported that it may be readily moved to an unloading position, a loading position, of an operating position.

A further object of the invention is to provide a process of dyeing wherein the dye liquor is forced radially outwardly and inwardly through rotating compartments containing the material to be dyed, and wherein the direction of movement of the rotating compartments is reversed, so as to facilitate the passing of the dye liquor through the material.

In the drawings, which show by way of illustration one embodiment of the invention, Figure I, is a longitudinal sectional view through a dyeing machine having my improvements applied thereto. Fig. II, is a transverse sectional view on the line II-II of Fig. I. Fig. III, is a similar sectional view, showing the tank for the dye liquor moved to a loading position. Fig. IV, is a view similar to Fig. III, showing the tank moved to unloading position. Figs. V, and

VI, are diagrammatic views illustrating the change of conditions in the behavior of the material within the rotating cage, due to the reversal of its motion within the dye liquor tank.

The invention consists generally in providing a supporting tank for the dye liquor, which is preferably substantially cylindrical in shape, with an opening in one side extending from end to end thereof, through which the tank may be loaded or unloaded. This tank is also so mounted that it may be rotated to place the same in the most convenient position for unloading, and also in the most convenient position for loading.

Within the tank is a rotating cage which is preferably perforated throughout, and is formed with a central perforated section providing a central chamber, in which oppositely disposed propellers may be placed. This central chamber communicates with the tank through suitable openings in the end walls of the cage, so that the dye liquor may be drawn from the tank into the central chamber by the propellers, and forced outwardly through the inner perforated cylindrical section to all parts of the cage and through the outer perforated section of the cage, thereby establishing a circulation of the dye liquor in and about the material being dyed. A rotation of the propellers in the opposite direction will cause the dye liquor to pass into the cage through the outer perforated parts thereof, and thence into the inner chamber and out through the end openings into the tank.

Referring more in detail to the drawings, my improved dyeing machine consists of a main supporting frame 1, on which is pivotally mounted a tank 2. The tank 2, is provided with projecting end trunnions 3, which are supported in suitable bearings in the frame 1. This tank, as clearly shown in Figs. II, III, and IV, is substantially cylindrical in shape, and is provided with an opening 4, which extends from end to end thereof. The tank is bent outwardly as at 5, to form side walls for the opening 4. The tank is preferably formed in two sections, secured together by suitable bolts 6. The object of making the tank in sections is to permit the insertion of the supporting cage. The main frame 1, is also provided with rollers 7, and 8, which engage the outer surface of the tank, and assist in supporting the same.

Secured to one end of the tank, is a rack segment 9, which is concentric with the axis of the tank, and engaged by a pinion 10. This pinion 10, is mounted on a short shaft 11, having an operating handle 12. By rotating the shaft 11, the pinion 10, will cause the tank to turn on its supporting trunnions 3, 3, so that the tank may be shifted from the position shown in Fig. II, 10 to the position shown in Fig. III, or to the position shown in Fig. IV.

Located within the tank is a supporting cage 13, also cylindrical in outline, and this supporting cage is rotatably mounted on 15 suitable bearings 14, and 15. The bearing 14, is formed as an extension of the supporting trunnion for one end of the tank. The bearing 15, is carried by a bracket 16, bolted to the inner face of the tank 2. The outer 20 wall of the cage is perforated, as clearly indicated in the drawings, and each end wall 17, and 18, is also perforated. The cage is provided with a central perforated tubular section 19, which, as herein shown, is hexagonal in cross section. Radial partitions 20, extend from the vertexes of the angles of this central section to the outer wall of the cage, and these partitions are likewise perforated. The radial partitions form separate 25 compartments within which is placed the material to be dyed. The outer wall of the cage is provided with a door for each compartment, to permit the insertion and the removal of the material to be dyed. The inner section 19, forms a tubular chamber 21, and this chamber communicates with the tank through openings 22, extending through the end walls in the cage. Extending longitudinally through the central 30 chamber 21, is a shaft 23, on which are mounted two oppositely disposed propellers 24. These propellers are adjacent the ends of the compartment 21. The shaft 23, is journaled in the bearings for the cage, and 35 protrudes at one end to support a gear wheel 25. This gear wheel meshes with an idler 26, journaled on the bracket 16. The cage is formed with an annular rack 27, with which the idler 26, meshes. The annular 40 rack is toothed on its inner and outer peripheries. A gear wheel 28, meshes with the teeth on the outer periphery of the rack, and is mounted on a suitable shaft 29, carried at the upper end of the tank. A 45 sprocket wheel 30, is mounted on the outer end of the shaft 29, and this sprocket wheel is geared by a suitable chain 31, to a sprocket wheel 32, on a shaft 33, driven by a sprocket chain 34, from any suitable source of power. 50 Rotation of the shaft 29, through the shaft 33, will cause the gear 28, to rotate the cage 13. This motion of the cage 13, through the idler 26, will cause the driving of the gear 25, and the shaft 23, connected thereto. The 55 same means, therefore, which rotates the

cage, also drives the propellers 24. If the cage is rotated in the opposite direction, the propellers will be correspondingly oppositely driven.

It will be noted that the mechanism for 70 rotating the cage is connected thereto through the open mouth of the tank, which obviates the extension of the operating shafts through stuffing boxes in the end walls of the dye liquor-containing tank. It 75 will also be noted that when the cage is rotating in the direction indicated by the arrow in Fig. V, the material under treatment, which is constantly immersed in the dye liquor, will lag and be packed or compressed 80 more densely against the vertical perforated partitions in the rear of the direction of rotation, as clearly shown in the figure by the heavier shading. The dye liquor as it is forced outwardly by the propellers lags 85 backward. This results in a more open mass of goods on the opposite sides of these partitions and this condition tends to facilitate the circulating of the dye liquor. When the direction of rotation of the cage 90 is reversed, as shown in Fig. VI, the conditions are exactly reversed and the portion of the compartment or pocket which was before densely packed becomes relaxed and the material becomes packed or compressed 95 against the opposite partition of the compartment. This reversing of the direction of rotation of the cage and the shifting of the material from one side of the compartment to the other results in a spongelike 100 action in regard to the taking up of the dye liquor, *i. e.* the materials are alternately relaxed and compressed, thereby greatly facilitating the absorption of the dye stuffs. This compression and relaxation of the material also produces a change in the direction of flow of the dye liquor. When the propellers are rotating in the opposite direction and the dye liquor flows inward instead of outward, practically the same action 105 occurs.

In the operation of my device, the hand shaft 11, is turned so as to move the tank to a convenient position for the placing of the material in the supporting cage. This 115 position of the tank is illustrated in Fig. III, of the drawings. The cage is then rotated so as to bring one compartment after another directly in rear of the entrance to the tank; the doors of the compartments 120 are raised and the material inserted, after which the doors are closed and another compartment is made accessible and likewise filled. After the machine is loaded with the material to be dyed, the tank is turned to 125 an upright position, as shown in Fig. II, through the aid of the hand shaft 11. The cage is then set into rotation through the operating mechanism therefor, and this in turn causes the driving of the propellers 130

24. If the propellers are driven in one direction, the dye liquor will be drawn in through the openings in the end walls of the cage, and will be forced radially outwardly through the compartments and the perforations in the outer wall of the cage. When the propellers are driven in the opposite direction, the dye liquor is drawn in through the outer wall of the cage, and 10 through the perforations in the central section to the inner compartment, and is forced by the propellers through the openings in the end walls into the tank. The dye liquor may thus be circulated in either direction 15 through the articles under treatment.

By providing a propeller at each end of the central compartment of the cage, one propeller coöperates with the other to force the liquor radially outwardly through the 20 cage, or in turn to draw the liquor radially inwardly through the cage. After the material has been dyed, the dye liquor can be readily withdrawn from the tank if desired, by any suitable means, and the tank 25 turned to the position shown in Fig. IV, which renders the supporting cage readily accessible for unloading the dyed material from the compartments.

From the above, it will be apparent that 30 I have also devised a new process of dyeing, which consists in moving the material under treatment in mass back and forth in the dye liquor, whereby the densely packed portions of the mass are shifted and 35 at the same time the dye liquor is caused to circulate across the path of movement of the material.

It is obvious that minor changes in the 40 details of construction and arrangement of parts may be made, without departing from the spirit of the invention as set forth in the appended claims.

Having thus described my invention, I 45 claim:

1. A dyeing machine including in combination, a tank for the dye liquor, a rotatable perforated cage located within said tank, said cage having an inner perforated section forming an inner chamber, said cage 50 having openings leading from the tank to said inner chamber, oppositely disposed propellers located in said inner chamber, and means for rotating said propellers.

2. A dyeing machine including in combination, a tank for the dye liquor, a rotatable perforated cage located within said tank, said cage having an inner perforated section forming an inner chamber, said cage 55 having openings leading from the tank to said inner chamber, oppositely disposed propellers located in said inner chamber, and means for simultaneously rotating said cage and said propellers.

3. A dyeing machine including in combination, a tank for the dye liquor, a rota-

table perforated cage located within said tank, said cage having an inner perforated section forming an inner chamber, said cage 70 having openings leading from the tank to said inner chamber, oppositely disposed propellers located in said inner chamber, said propellers being located respectively adjacent the ends of the chamber, and means for rotating said propellers in either direction.

4. A dyeing machine including in combination, a tank for the dye liquor, a rotatable perforated cage located within said tank, said cage 75 having a central perforated section forming an inner chamber, and perforated radial partitions extending from said inner section to the outer wall thereof for dividing said cage into separate compartments, said cage having openings leading through the end walls of the cage to said inner chamber, oppositely disposed propellers located respectively in said inner chamber adjacent the ends thereof, and means for rotating said propellers.

5. A dyeing machine including in combination, a tank for the dye liquor, a rotatable perforated cage located within said tank, said cage having a central perforated section forming an inner chamber, and perforated radial partitions extending from said inner section to the outer wall thereof 90 for dividing said cage into separate compartments, said cage having openings leading through the end walls of the cage to said inner chamber, oppositely disposed propellers located respectively in said inner chamber adjacent the ends thereof, and means for simultaneously rotating said cage 95 and said propellers.

6. A dyeing machine including in combination, a tank for the dye liquor, a rotatable perforated cage located within said tank, said cage having a central perforated section forming an inner chamber, and perforated radial partitions extending from

said inner section to the outer wall thereof 100 for dividing said cage into separate compartments, said cage having openings leading through the end walls of the cage to said inner chamber, oppositely disposed propellers located respectively in said inner chamber adjacent the ends thereof, said cage 105 having an annular rack thereon, means extending through the open mouth of the receptacle and engaging said rack for rotating the cage, and means operated by said rack for rotating the propellers.

7. A dyeing machine including in combination, a tank for the dye liquor, a rotatable perforated cage located in said tank, supporting bearings for said cage, a propeller shaft disposed axially of the cage and having one end thereof extending through a bearing for the cage, a perforated section in said cage forming an inner chamber surrounding said propeller shaft, said cage 125 hav-

ing openings leading from said chamber to the end walls thereof, propellers mounted on the propeller shaft at each end of the chamber, said propellers being oppositely disposed, a gear mounted on the end of the propeller shaft, a gear mounted on a bearing on the tank and engaging said gear on the propeller shaft, an annular gear having an inner toothed section engaging the gear on the tank, a gear mounted on a bearing carried by said tank and extending through the opening in the tank and engaging an outer toothed section on said annular gear for rotating said cage and the propeller shaft.

8. A dyeing machine including in combination, a tank for the dye liquor, means for pivotally supporting said tank, a perforated cage mounted in said tank, means for rotating said cage, and means whereby said tank may be shifted on its pivotal support for positioning the same for loading and unloading.

9. A dyeing machine including in combination, a tank for the dye liquor, means for pivotally supporting said tank, a perforated

cage mounted in said tank, means for rotating said cage, means whereby said tank may be shifted on its pivotal support for positioning the same for loading and unloading, a supporting frame for said tank, said supporting frame having rollers mounted thereon engaging said tank for forming an auxiliary supporting means therefor.

10. A dyeing machine including in combination, a tank for the dye liquor, means for pivotally supporting said tank, a perforated cage mounted in said tank, means for rotating said cage, means for causing a circulation of the dye liquor across the path of movement of the material to be dyed, and means whereby said tank may be shifted on its pivotal support for positioning the same for loading and unloading.

In testimony whereof, I have hereunto signed my name, at Philadelphia, Pennsylvania, this twenty-eighth day of March, 1914.

WILLIAM H. SHAINLINE.
